UNITED STATES PATENT OFFICE

121,072

DESIGN FOR A CHAIR

Walter J. Johnson, Chicago, Ill., assignor to Johnson Chair Company, Chicago, Ill., a corporation of Illinois

Application October 18, 1939, Serial No. 87,708

Term of patent 7 years

To all whom it may concern:

Be it known that I, Walter J. Johnson, a citizen of the United States, residing at Chicago, in the county of Cook and State of Illinois, have invented a new, original, and ornamental Design for a Chair, of which the following is a specification, reference being had to the accompanying drawing, forming a part thereof.

In the drawing:

I claim:

The ornamental design for a chair, substantially as shown.

WALTER J. JOHNSON.
